UNITED STATES PATENT OFFICE.

SANFORD A. MOSS, OF LYNN, MASSACHUSETTS, ASSIGNOR TO GENERAL ELECTRIC COMPANY, A CORPORATION OF NEW YORK.

ERNEST A. GIBSON, JR.

ELASTIC-FLUID TURBINE.

1,105,820.

Specification of Letters Patent.

Patented Aug. 4, 1914.

Application filed April 3, 1914. Serial No. 829,227.

To all whom it may concern:

Be it known that I, SANFORD A. Moss, a citizen of the United States, residing at Lynn, county of Essex, State of Massachusetts, have invented certain new and useful Improvements in Elastic-Fluid Turbines, of which the following is a specification.

The present invention relates to turbines and particularly to a turbine having a plurality of stages, the final stage being connected to exhaust into a condenser. In connection with the operation of such turbines it sometimes happens that the condenser vacuum is lost and the turbine is called upon 15 to operate non-condensing. Under these circumstances the efficiency of the turbine is improved by permitting the turbine to exhaust from an intermediate stage direct to atmosphere, thereby cutting off the final 20 stages.

According to the present invention I provide a valve controlling a passage leading from an intermediate stage of the turbine and automatic means for opening the valve 25 when the vacuum is lost and reclosing it when the vacuum is regained.

The drawing is a plan view of a somewhat diagrammatic nature illustrating an embodiment of my invention. 30 2 is a high pressure turbine receiving motive fluid by way of conduit 3 and exhausting through conduit 4 to the condenser 5. The turbine is here shown as being of the Curtis or impulse type as being connected to 35 drive a generator 6. Leading from an intermediate stage of the turbine is the conduit 7 in which is arranged a suitable valve 8, preferably a double seat or balanced valve. This valve will preferably be water-sealed as

40 shown at 9, a suitable gage 10 being provided to indicate the level. Connected to the stem of the valve is a movable abutment, here shown as a piston 11, operating in the cylinder 12. The one side of the piston is subjected to the pressure of the condenser through the pipe 13, the other side being subjected to a substantially constant pressure as atmospheric. The valve is biased to 45 open position as by the adjustable weight 14 on the lever 15. It will be understood that the pressure responsive device illustrated and the biasing means are only by way of example and that I may use other forms, as found desirable. By using a balanced valve 50 as shown at 8 variations in the pressure in

the intermediate stage to which the conduit 7 is connected will not in any way affect the movable abutment 11. The only way the valve can be opened is by a failure of the vacuum.

In operation, so long as the condenser vacuum is maintained the constant pressure on the one side of the movable abutment, here the upper side, will be sufficient to seat the valve against the biasing force tending to 60 open it. If, for any reason, the vacuum is lost, the pressure of the condenser will then tend to equalize the constant pressure and permit the biasing force to open the valve. Should the condenser vacuum be restored, 65 70 the valve will be automatically reseated as will be obvious.

In accordance with the provisions of the patent statutes, I have described the principle of operation of my invention, together 75 with the apparatus which I now consider to represent the best embodiment thereof; but I desire to have it understood that the apparatus shown is only illustrative, and that the invention can be carried out by other 80 means.

What I claim as new and desire to secure by Letters Patent of the United States, is,—

1. The combination of a turbine having a conduit leading from an intermediate stage, 85 a balanced valve in said conduit, a movable abutment connected to the stem of the valve, a condenser, and a pipe connecting one side of said abutment to the condenser, the other side being subjected to a substantially constant pressure.

2. The combination of a turbine having a conduit leading from an intermediate stage, a balanced valve in said conduit, means for biasing the valve to open position, a condenser, a stem for the valve, a movable abutment connected to the stem, one side of which is subjected to substantially constant pressure, and a pipe connecting the other side of the abutment to the condenser.

3. The combination of a turbine, a conduit connected with an intermediate stage, a water sealed valve biased to an open position in the conduit, a cylinder, a piston therein, a stem connecting the valve thereto, and a pipe connecting the cylinder with the condenser so as to cause the valve to remain closed so long as the vacuum is maintained.

4. The combination of a turbine, a conduit connected with an intermediate stage, a valve 110

in the conduit biased to open position, a movable abutment connected to the valve, and means subjecting one side of the abutment to the pressure of the condenser, the other side being subjected to a substantially constant pressure, the pressure on said last-named side being opposed to the biasing force.

In witness whereof, I have hereunto set my hand this thirty-first day of March, 1914.

SANFORD A. MOSS.
